FUSE FOR ELECTRIC CIRCUITS

August Appel, Vienna, Austria

Application September 14, 1931, Serial No.
562,771, and in Austria September 19, 1930

5 Claims. (Cl. 200—123)

This invention relates to fuses of the type in which a switch member, on the attainment or overstepping of a certain temperature limit, performs a switching or cutting out action. Fuses 5 of this type are generally equipped with a switch member which is connected to a fixed member by means of solder of a suitably low melting point, and which is subjected to the pressure or tension of a spring. For the heating and melting 10 of this soldered connection there is usually employed a small heating coil interposed in the circuit to be fused. Fuses of this type, as employed more particularly in connection with automatic telephone systems, suffer, however, from the drawback that often mere softening of the 15 solder and partial cutting out of the current supply take place, thus giving rise to the loose contacts which are so troublesome and generally so difficult to trace in such systems. After 20 repeated use the solder also becomes easily altered as to its composition, and therefore also in its melting point, so that there are considerable variations in the temperature and time required for melting between fuses which are supposed to be identical. Moreover the quantity of 25 solder applied varies, and exercises an indeterminate influence on the actual time required for melting the same. Further, in the case of 30 interiorly situated and inaccessible fuses it is practically impossible to check the quality of the soldering work, so that it not infrequently happens that such fuses become loosened or 35 broken by mere vibration or concussion.

Thermically operated switches for the protection of machines and apparatus from over-heating are also already known, in which a slotted plate of a readily fusible metal retains under tension a switching rod which controls a current 40 circuit. In switches of this type the rod or other switching member proper must first be tensioned and held in position, after which a slotted plate or fork-shaped piece of the fuse metal is inserted between a specially shaped head on the said bar or member and a fixed portion of the switch. The insertion of new fuse elements thus requires 45 a number of operations and the use of elements specially made to suit the shape of the switch members. These circumstances become a source of very considerable inconvenience and loss of 50 time when a large number of fuses are replaced as in the case of automatic telephone systems.

The present invention obviates the above-mentioned drawbacks, and provides a non-soldered 55 fuse responsive to excess current and excess volt-

age in which a switch member heated by the current is held in tension by a plate of the fuse metal, and is adapted to interrupt the current circuit by a movement relative to a second switch member on the attainment or overstepping of a certain maximum strength of current. In accordance with the invention, the fuse consists of two detachably connected parts of which the one contains the spring-tensioned switch member, and the other provides the counter support 60 therefor and receives the loosely inserted fuse plate, so that by the mere bringing together of these two parts the movable switch member is tensioned and the fuse plate positioned between the two members as required. Thus to remove 65 the used fuse plate it is merely necessary to disconnect the two parts, and after the insertion of a fresh fuse plate it is merely necessary to bring the two parts together again in order to put the fuse into working order. In the simplest form 70 of construction the movable switch member takes the form of a pin subjected to spring action and adapted to be heated by a heating coil traversed by the current to be checked. In order to prevent the fuse metal when melted from dropping 75 and lodging in the adjacent mechanism the invention is further developed to comprise a modified form of fuse in which, instead of the movable pin being heated, the heating coil is applied to a tubular member which forms the counter support 80 for the plate of fuse metal. The pin as before is pressed by a spring against the middle of the fuse plate. But in this case the fuse plate is heated annularly by the supporting end of the 85 said tubular member, so that when the fuse metal has become sufficiently softened the shearing strain between the outer edge of the end of the switch rod or pin and the inner edge of the supporting end of the tubular member coupled with the force of the spring causes the middle of 90 the fuse plate to be punched out, thus liberating the pin to move in response to the spring. Since in this case no actual melting of the fuse metal takes place no clogging or unintentional soldering 95 together of other parts of the mechanism can possibly occur, and the fuse plate scrap can all be used again. The fuse discs are preferably made of metal alloys the softening point of which is considerably below the melting point. Examples of such alloys are certain of the known varieties of Wood's metal.

In the accompanying drawing the invention is illustrated, by way of example, in the form of a so-called heating coil fuse as employed in automatic telephone systems, Fig. 1 showing, in sec-

tion, a form of construction in which the switch pin is heated, and Fig. 2, likewise in section, a form in which a tubular counter supporting member for the fuse plate is heated.

5 Referring to Fig. 1, a cartridge-shaped metal case 1 is traversed axially by a metal pin 2, these two parts being insulated from each other by means of a bush or plug 3 of insulating material inserted in the case. The pin 2, which may consist of drawn copper wire, has attached to it a disc 4 of insulating material which can slide with an easy fit in the case 1. A helical spring 5 is inserted and adapted to be compressed between this disc 4 and the plug 3. The pin 2 is further 10 fitted with a plate of insulating material 6 which is provided with a metallic ring 7 of good conducting material. Between the two discs 4 and 6 there is wound upon the pin 2 the heating coil 8 of resistance wire the one end of which is connected to the pin 2 and the other end to the ring 7. A cap 10 having a central hole is adapted to be fitted over the open end of the case 1, and to be attached thereto by means of a bayonet joint or in any other manner permitting of ready disconnection. Into this cap 10 there is inserted an 15 insulation ring 11 with a conically tapered or shouldered rim for the reception and centralization of the fuse plate 12. This plate is held in position by the end of the pin 2 which is pressed firmly thereon by the spring 5. The complete 20 fuse is interposed in the current circuit by means of the spring 15 and of a metal ring 13 with a projecting tongue 14 inserted between the end of the case 1 and the plug 3. 16 denotes a contact 25 spring with which, after the melting of the fuse plate 12, the pin 2 comes into contact, as indicated by the position of the pin 2 shown in dotted lines in the drawing.

30 The mode of operation of the fuse is as follows:—The current flowing through the fuse passes from the spring 15 through the copper pin 2 into the heating coil 8 consisting of wound resistance wire and thence to the ring 7. From this ring the current passes through the tongues 35 9 into the casing 1 which is connected through the metal ring 13 and tongue 14 to the supply line. When the current in the fused circuit increases beyond a certain permissible limit the copper pin 2 is heated by the heating coil to such 40 an extent that the pin can perforate the fuse plate 12, and is ejected by the spring 5 through the hole in the head of the cap 10 to form contact with the earthed contact spring 16, as indicated in dotted lines in the drawing. This movement 45 of the pin renders the heating coil 8 dead and inoperative, and at the same time operates a signalling device which is connected into the earthing line, and which signals optically or acoustically the breaking of the fuse.

50 In the modified form of construction shown in Fig. 2, the fuse consists essentially of a cylindrical metal sleeve 17 which is reduced at one end. The open end is covered by a metal cap 18 which is bayonet-jointed or otherwise detachably connected to the sleeve 17. Within the sleeve 17 and insulated therefrom there is slidably mounted a pin 20 which is guided by two discs 21 and 22 of insulating material inserted in the sleeve 17. A helical spring 23 which bears with its one end 55 against the insulation disc 21 and with its other end against a collar 24 on the pin 20 tends to press the pin 20 against the cap 18. In the cap 18 there is mounted by means of flanges 25 and 26 of insulating material 60 a small metal tube 27 the bore of which is equal

to the diameter of the pin 20, so that this pin can pass therethrough under the thrusting action of the spring 23. The outer edge of the end of the pin 20 and the inner edge of the end of the tube 27 are adapted to cooperate with a shearing action, in the manner of a die punch. The one flange 25 is cupped to receive the fuse plate 28. The tube 27 is fitted with the heating coil 29 the one end of the wire of which is connected to the tube 27, while the other end is connected to the cap 18 and therefore also with the sleeve 17. The cap 18 is provided with a hood-like extension 30 with an opening 31 for the reception and removal of the punched-out portions of the fuse plates. A projection 32 on the sleeve 17 serves for the attachment of the fuse to its holder.

65 As will be seen from the drawing (Fig. 2), the current to be limited passes through a contact spring (not shown) into the pin 20 the one end of which projects sufficiently far from the end of the sleeve in consequence of the fact that the other end of the same is retracted against the action of the spring 23 and rests against the fuse plate 28 supported by the end of the tube 27. The current then travels through the pin, fuse 70 plate, tube 27, heating coil 29, and into the cap 18 and sleeve 17.

75 The heating of the tube 27 causes the fuse plate pressed against the end thereof, when the current reaches a certain limit, to be softened to such an extent that the force of the spring 23 causes the middle of the fuse plate to be punched out and thrust by the movement of the pin 20 into the hood 30 from which it can be removed through the opening 31. The presence of this hood prevents the punched-out portions of the fuse plates from becoming lost or from causing short-circuiting or other derangement in the apparatus in which the fuse is used. The forward movement of the pin 20 under the action of the spring 105 23 interrupts the current circuit by bringing the end of the pin out of contact with the lead-in contact spring. As already mentioned, with this form of fuse the fuse plate is perforated without being melted, so that there is no danger of clogging or of soldering together parts of the adjoining mechanism, and the fuse is reset for operation by the simple insertion of a new plate.

80 I claim:—

1. In a fuse for electric current circuits of the 125 type in which a switch member heated by the current is caused to execute a switching action by movement relative to a second switch member on attainment or overstepping of a current limit, and in which a plate of easily fusible metal is 130 interposed in the path of the said movable switch member for the purpose of retaining the same in its normal position, a casing consisting of two detachably interconnected parts, a movable switch member in the one of the said parts, a 135 spring adapted to press the said member in an axial direction, the second of the said two parts adapted to serve as a counter support to the said member, and a plate of easily fusible metal loosely inserted in the said second part, the said parts 140 and the said member being so dimensioned that the said plate is brought into position between the said member and the said second part of the casing and the said member is put under tension against the action of the said spring by the mere 145 action of bringing the two said parts together.

2. In a fuse as claimed in claim 1, the said two parts consisting of a sleeve and a cap, respectively, interconnected by means of a joint adapted to be readily taken apart and reassembled by hand 150

without the use of tools, the said member consisting of a pin, and a heating coil consisting of resistance wire being interposed in the current circuit and wound about the said pin.

5 3. In a fuse as claimed in claim 1, and of the type comprising a tubular member and a heating coil wound about the said tubular member, the said member being adapted to serve as a counter-support for the loosely inserted plate of readily 10 fusible metal, and being open at both ends, for the purpose of enabling a stamped-out portion of the said plate to pass unhindered through and out of the said tubular member.

15 4. In a fuse as claimed in claim 1, the said movable switch member being a pin slidably mounted within and insulated from the said first

part of the casing, and the said second part of the casing being a cap detachably connected to the said first part, a tubular member of a bore substantially equal to the diameter of the said pin and adapted to serve as a counter support 80 for the plate of easily fusible metal, and a heating coil of resistance wire interposed in the current circuit and wound about the said tubular member, the said cap being adapted to establish electric connection between the one end of the 85 said heating coil and the said casing.

5. In a fuse as claimed in claim 1 a hood-shaped extension on the said second part of the casing for the reception of the detached portion of the plate of easily fusible metal. 90
